UNITED STATES PATENT OFFICE.

DANIEL E. ERICKSON, OF BERKELEY, CALIFORNIA, ASSIGNOR TO R. S. MOORE, OF SAN FRANCISCO, CALIFORNIA.

OIL-BURNING FURNACE.

1,122,068.

Specification of Letters Patent. Patented Dec. 22, 1914.

Application filed May 8, 1914. Serial No. 836,689.

To all whom it may concern:

Be it known that I, DANIEL E. ERICKSON, a citizen of the United States, residing at Berkeley, in the county of Alameda and State of California, have invented certain new and useful Improvements in Oil-Burning Furnaces, of which the following is a specification.

The present invention relates to improvements in oil burning furnaces, and more particularly to an air heating and regulating device adapted for use in co-operation with the fuel burner, and the invention has for its principal objects to provide a device forming an air chamber and by the use of which the quantity of air is admitted to the air chamber to circulate around the burner and assist in the complete combustion of the gases without permitting the glare or reflection of the burner flame to be in a line with the inlet openings through which the air is admitted; to provide a novel form of air chamber which is capable of attachment to the exterior of any well known type of furnace without altering the same, and to provide a novel form of burner shield and a burner adjustment whereby the position of the burner within the chamber may be readily varied.

With the above mentioned and other objects in view, the invention consists in the novel construction and combination of parts hereinafter described, illustrated in the accompanying drawings, and pointed out in the claims hereto appended; it being understood that various changes in the form, proportion, size and minor details of construction within the scope of the claims, may be resorted to without departing from the spirit or sacrificing any of the advantages of the invention.

To more fully comprehend the invention, attention is directed to the accompanying sheet of drawings, wherein is disclosed the preferred form of my invention and in which—

Figure 1 is a vertical sectional view of my improved device mounted on the front wall of a furnace adjacent the door opening thereof. Fig. 2 is a front elevation of my improved device disclosing the shape of the same and the swinging air inlet gates.

Referring more particularly to the drawings, wherein like characters of reference designate corresponding parts throughout

the several views, the numeral 1 designates the front wall of a furnace provided with the usual door opening 2 which communicates with the furnace fire box, and over the front wall of the furnace is positioned, in any suitable manner, the fire front 3. Secured to the fire front 3 by the bolts 4 and surrounding the opening 2 is the annular supporting member 5 substantially L-shaped in cross section and to the outwardly projecting flanged portion of which is secured, by the rivets 6, the cylindrical shell or housing 7 which forms an air chamber 7' in front of the door opening 2, and said shell or housing carries on its outer peripheral edge 78 a facing ring 8, which is secured to the outer peripheral edge of the shell or housing by the angle braces 9.

Extending diametrically across the outer open end of the shell or housing 7 and secured to the facing ring 8, is a support 10 which divides the outer circular open end of the shell or housing 7 into two semi-circular air inlet openings each of which is controlled by an inwardly swinging gate 11, hinged at one edge, as at 12, to the opposite side edges of the support. The free edges of the gates 11 carry suitable toothed racks 13 which are pivotally connected thereto by brackets 14 and said racks when the gates are swung inwardly to an open position, engage the inner peripheral edge of the facing ring 8 and retain the gates in their adjusted position. The rack associated with the upper gate is preferably forced upwardly in contact with the facing ring by a spring 15. The support is provided in its center with a suitable opening surrounded at one side by a collar 16 secured to the plate and through said opening and collar extends into the air chamber in front of the door opening 2, the pipe 17 carrying on its inner end a suitable burner shield 18 which extends at right angles from the end of the pipe and said burner shield is preferably formed with small openings or slots 19.

The burner shield prevents the direct current of air passing through the air chamber from striking the flame and extinguishing the same, and also provides a means for super-heating the air immediately before the same intermixes with the flame issuing from the burner. The pipe 17 is capable of adjustment through said collar and opening to vary the position of the burner shield 110

relative to the opening 2 and said pipe is retained in its adjusted position by the set screw 20 threaded through the collar 16. A conduit 21 extends through the pipe 17 and carries on its inner end a suitable fuel atomizer or burner 22 which normally projects a slight distance beyond the burner shield 18 and said conduit is connected at its opposite end to a suitable coupling 23 carrying a valve 24 which controls the flow of fuel from a suitable flexible feed pipe 25. The coupling 23 extends through a ball casting 26 mounted on the end of the pipe 17 by set screw 27, and said coupling is retained in position in said casting by the adjusting screw 28 which extends through said casting. A suitable sight opening 29 is formed in one of said gates and the same is normally covered by a pivotally mounted cover or disk.

It will be apparent by examining Fig. 1 of the drawings, that when the gates 11 are swung inwardly, as in the dotted lines, air will be admitted through the openings controlled thereby in the front wall of the air chamber and the gates will prevent the direct glare from the burner flame from being in a direct line with the air inlet openings controlled by the gates.

30 By my improved construction, I have provided a device which is capable of attachment to any well known type of furnace without altering the same, and without the necessity of the furnace being formed with heating chambers or compartments therein. I have also provided a device which is adapted for positioning over the furnace door opening to provide the air chamber exterior of the furnace front wall, and one 35 in which the burner and burner shield are capable of adjustment relative to the furnace door opening to regulate the position of the burner and shield within the air chamber, and have provided a swinging 40 gate structure which is so constructed as to enable air to be admitted into the air chamber without forming an opening in direct alinement with the burner and the exterior 45 of the air chamber through the door opening. By providing upper and lower swinging 50 gates for admitting air into the air chamber, I am enabled to admit air both above and below the burner and am also 55 enabled to control one air supply independently of the other.

Having thus described my invention what I claim as new and desire to protect by Letters Patent is:—

1. In a device of the class described, a 60 furnace formed with a door opening leading to the fire box, an air chamber secured to the furnace front wall and surrounding said door opening, a fuel burner extending

through the front wall of said air chamber and discharging into said air chamber in front of said door opening, a burner shield surrounding said burner, means for admitting air to said air chamber and comprising a movable gate supported by the walls of said chamber, said gate when in open position providing a passage for the admittance of air into said chamber, and adapted to intersect a direct line from said burner flame to the air inlet opening in said chamber. 75

2. In a device of the class described, a furnace with a door opening leading to the fire box, an air chamber secured to the furnace front wall and surrounding said door opening, a support carried by said air chamber, a burner extending into said air chamber and adjustably mounted in said support, a burner shield surrounding said burner, a flexible connection for feeding fuel to said burner, inwardly swinging gates hinged to 80 said support for admitting air into said air chamber, and means for retaining said gates in their adjusted position.

3. In a device of the class described, a furnace formed with a door opening communicating with the fire box, an air chamber detachably secured to the furnace front wall and surrounding said door opening, a support extending across the front of said air chamber, upper and lower inwardly 90 swinging gates hinged to the opposite side edges of said support, means carried by the gates for retaining the same in their adjusted position, a tubular member extending through said support into said air chamber 95 and adjustable therein, a burner shield carried by one end of said tubular member, a burner mounted in said tubular member adjacent said shield, and a flexible fuel supply pipe connected to said burner. 100

4. In a device of the class described, a furnace formed with a door opening communicating with the fire box, an air chamber detachably secured to the furnace front wall and surrounding said door opening, a support extending across the front of said air chamber, upper and lower swinging 110 gates hinged to the opposite side edges of said support, means carried by the gates for retaining the same in their adjusted position, and a burner adjustably mounted in said support and extending into said air chamber. 115

In testimony whereof I have signed my name to this specification in the presence of 120 two subscribing witnesses.

DANIEL E. ERICKSON.
